ADOLPH F. RIETZEL, OF CHARLESTOWN, RHODE ISLAND, ASSIGNOR TO UNIVERSAL ELECTRIC WELDING COMPANY, OF LONG ISLAND CITY, NEW YORK, A CORPORATION OF NEW YORK.

METAL FABRIC.

1,162,402.

Specification of Letters Patent. Patented Nov. 30, 1915.

Original application filed October 21, 1908, Serial No. 458,818. Divided and this application filed November 16, 1909. Serial No. 528,278.

To all whom it may concern:

Be it known that I, ADOLPH F. RIETZEL, a citizen of the United States, and a resident of Charlestown, in the county of Washington and State of Rhode Island, have invented certain new and useful Improvements in Metal Fabrics, of which the following is a specification.

My invention relates to metal fabrics comprising members crossing one another and adapted for various uses, as for instance, fencing, lathing, etc.

My invention is useful for metal wire fabrics and for such fabrics when constructed in proportions for use as fencing and, in setting forth the invention, I will, for purposes of illustration only, describe the invention as embodied in wire fencing.

Various expedients have been resorted to for securing crossing members of a metal fabric to one another at their intersections, such as the use of a piece of wire bent or coiled around the members of the fabric, or the bending of the wires of the fabric itself, or a simple welding of the crossing members of the fabric to one another at the point of intersection or the interweaving of the wires with a ring.

The object of my present invention is to provide a simple, cheap, rigid and yet light structure and one which may readily and conveniently be manufactured in an electric welding machine.

The invention consists in the construction of metal fabric, as hereinafter more particularly described and then specified in the claims.

Referring to the drawings, Figure 1 shows a section of wire fencing constructed according to my invention. Fig. 2 is an enlarged side elevation at one of the intersections. Fig. 3 is a vertical section through the strand member and fastener of Fig. 2. Fig. 4 is a vertical section through a strand member and fastener of a modification. Fig. 5 is an elevation of another modification and Fig. 6 is an edge view of the same, one of the crossing or intersecting wires of the fabric being shown in cross-section. Figs. 7 and 8 illustrate some modifications in the form of the fastener. Fig. 9 illustrates a modification in which the fastener is applied to both sides of the fabric.

In the various figures of the drawings 1

indicates the strand or longitudinal members 55 of a metal fabric and 2 the stay, crossing or transverse members of the fabric or vice versa.

3 indicates the fastener made of a piece of wire bent around into any desired shape so 60 as to be capable of engaging, by its side, upon the sides of the crossing members 1, 2 of the fabric:

In Figs. 2, 4, 5, 7 and 8, the fastener is a single piece of wire cut to suitable length 65 and bent to the desired form and so as to extend completely around the crossing point of the fabric members 1 and 2 for making side contact with each of said members at two points located respectively at opposite 70 sides of the crossing point. A lateral bend or offset may be formed in one or both wires or members 1, 2, where they cross as at 5, in order that the wire fastener may more readily make contact by its side with the 75 fabric at the four points surrounding the intersection when it is superposed on both members. The fastener might however lie between the fabric members as indicated in Figs. 5 and 6. This modification renders it 80 unnecessary to bend either of the wires 1 and 2 or the wire fastener transversely to the plane of the fabric. Again the fastener might itself be slightly bent or distorted as shown in Fig. 4 to permit it to make side 85 contact readily with both of the crossing members in case it is desired to make up a fabric without any bending of said members at the crossing point. When the fastener is a single piece of wire bent to form, its opposite ends 4 are preferably located over one 90 of the members 1, 2, and are side-welded at that point as shown in Figs. 2, 5, 7, 8, to prevent the ring or other endless form of fastener from opening or the ends from becoming 95 displaced with reference to one another, as well as for securing greater rigidity or stiffness at all points.

The fastening piece of wire and the crossing members are superposed on one another 100 at the intersections as shown in the various figures and the rounded side of the fastening wire 3 engages the sides of the two crossing members of the fabric at points 7 and is welded thereto at such points of contact by heating current and pressure applied sidewise to the fabric in a welding machine 105 having suitable contact and pressure jaws

or electrodes. The pressure and contact electrodes of such a machine are indicated at 6, 6' Fig. 3. In constructing the fabric, they are applied at opposite sides of the fabric in obvious manner and in addition to being of form to squeeze the fastener and fabric members together, at their points of side contact, they also feed an electric heating current to the work which passes across 10 said contact points where the rounded side of the fastener makes limited electric contact with the fabric members, thereby facilitating the heating of the parts to the welding temperature in the electric welding or 15 uniting operation.

By my invention a metal fabric of great stiffness and strength and small weight may be produced at low cost. When the crossing members have a rounded side as in the case 20 of a wire fabric, this conduces to the formation of an initial electric contact spot or point of limited superficial area where the fastener crosses and makes contact by its side with the side of the strand or stay 25 member.

Obviously for great strength a fastener may be applied to both sides of the fabric at the intersections in the manner already described in which cases the points of side 20 contact on the two fasteners would preferably be opposite one another, as indicated in Fig. 9.

My present application constitutes a divi-

sion of my prior application filed October 21, 1908, S. N. 458,818.

What I claim as my invention is:

1. A metal fabric having crossing members and a fastening piece superposed on one another at the intersection and side-welded together on the side of the fastening piece, said fastening piece lying between the crossing members.

2. A metal fabric comprising crossing wires and a bent piece of fastening wire bent to extend completely around the crossing point, superposed on one another and having the bent wire side-welded to both crossing wires and on one of them at a point where the two ends of the bent wire meet.

3. A metal fabric comprising crossing wires and fastening pieces consisting of wire bent to surround the intersections, said fastening pieces being located between the crossing wires and side-welded to both of them.

4. A metal fabric comprising crossing members and metal fasteners lying between the said members at their intersections and welded to both.

Signed at South Kingston, in the county of Washington and State of Rhode Island, this 12th day of November, A. D. 1909.

ADOLPH F. RIETZEL.
